Franklin E. Horne, Rte. 2, Brent, Ala. 35034

Filed Feb. 8, 1974, Ser. No. 440,848

Term of patent 14 years

Int. Cl. D10—06

U.S. Cl. D10—119

FIG. 1 is a top plan view of a turkey caller showing my new design, the bottom side being identical to the top side;

FIG. 2 is an end elevational view taken along the line 2—2 of FIG. 1, the end not shown being identical to the end shown;

FIG. 3 is a front elevational view taken along the line 3—3 of FIG. 1; and,

FIG. 4 is a rear elevational view taken along the line 4—4 of FIG. 1.

The strap is broken away in FIG. 1 to indicate indeterminate length and fragmentarily shown in FIG. 2 for convenience of illustration.

I claim:

The ornamental design for a turkey caller, as shown and described.
